Primary Examiner — Jeffrey D Asch(74) *Attorney, Agent, or Firm* — Gerald E. Hespos; Michael J. Porco; Matthew T. Hespos(57) **CLAIM**

The ornamental design for a mobile telephone, as shown and described.

DESCRIPTION

FIG. 1 is a perspective view of a mobile telephone in accordance with my design;

FIG. 2 is a front elevational view of the mobile telephone of FIG. 1;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom plan view thereof.

The broken lines shown in FIGS. 4 and 6 that are immediately adjacent to the shaded areas and define unshaded regions, represent the bounds of the claim, while all other broken lines are directed to environment and are for illustrative purposes only; the broken lines form no part of the claimed design.
